ATTORNEY.

UNITED STATES PATENT OFFICE

WALTER LOCKE, OF PHILADELPHIA, PENNSYLVANIA, ASSIGNOR TO EDGE MOOR IRON COMPANY, OF EDGE MOOR, DELAWARE, A CORPORATION OF DELAWARE

BENT TUBE BOILER

Application filed April 21, 1930. Serial No. 445,904.

My invention relates to bent tube boilers of the type in which two upper drums are connected to a lower drum by banks of bent tubes and in which the front upper and lower drums and the tube banks connecting these drums may be said to constitute the steaming element of the boiler and the rear upper and lower drums and tube banks connecting them may be said to constitute the water heating element of the boiler. In such boilers the steam spaces of the upper drums are connected and the steam is drawn from the boilers from the rear upper drum; where, as is now usually the case, boilers of this type are operated at very high pressures, the drums are necessarily made of somewhat restricted diameter and holding capacity and under certain conditions of operation the water level in the upper drums is liable to fall to an undesirably low level. It is also true that in such boilers when working at high duty very considerable bodies of steam are generated in the front tube bank, resulting in a great agitation of the water in the front upper drum and the carrying off by the steam issuing therefrom of considerable quantities of entrained water, as a result of which there is apt to be such agitation in the water level of the rear upper drum as to make the ascertainment of the true water level in this drum as by a water glass a matter of some difficulty in view of the fact that the water in this drum forms a part of the circulatory system of the water heating element of the boiler. The object of my invention is, in the first place, to provide an additional reservoir of water by which unduly rapid variations of water level in the boiler can be prevented, to provide improved means for separating entrained water from the steam issuing from the front upper drum and for the delivery of comparatively dry steam from the boiler and to provide a quiescent body of water the level of which will approximately indicate the true water level and my invention consists in providing in combination with a boiler of the type described a third upper drum located between and approximately at the level of the two upper drums of the boiler proper, the steam

space of which is connected with that of the two upper drums of the boiler proper and the water space of which is also connected with the water space of the rear upper drum so that water can flow freely from the intermediate upper drum to the rear upper drum when for any reason the water level in the rear upper drum falls. It is an essential feature of my invention that the intermediate upper drum should be disconnected from the main circulatory system of the boiler so that the water contained therein shall be free from agitation.

By preference I connect the intermediate upper drum with the lower drum by a row of water tubes located in the rear of the steaming section, such tubes functioning, where for any reason there is a rapid fall in the water level of the boiler, to supply water directly to the lower drum as well as to the upper rear drum and thus more promptly to equalize the water level in the steaming section of the boiler. The capacity and location of this row of water tubes are such as will not under any conditions bring about any considerable circulatory movement of the water in the intermediate drum but preferably, and as far as possible, I protect this row of water tubes from direct contact with the heating gases by baffles and in certain types of baffling I can and do utilize this row of water tubes to support a baffle which will protect them from direct contact with the gases while at the same time serving to give proper direction to the gases among the water tubes constituting a part of the main circulatory system of the boiler.

My invention will perhaps be better understood by describing it in connection with the drawings, which is a longitudinal vertical section through a boiler embodying my improvements and shown as located in a furnace and setting of the usual character.

A indicates the furnace. B the front upper drum; B¹ the lower drum; B² the rear upper drum and B³ the fourth drum, located at approximately the level of and between the upper drums but entirely unconnected with the tube banks provided for the circulation of water through the heating and

steaming elements of the boiler. C represents the bank of bent tubes located at the front of the steaming section. C¹ the bank of bent tubes located at the rear of the steaming section. C² and C³ make up the bank of bent tubes provided for the heating section consisting of a group of tubes C² through which water moves upward from the lower drum to the rear upper drum and another group of tubes C³ through which the water moves downward from the rear upper drum to the lower drum. D indicates a header extending parallel with and behind the rear upper drum and connecting through a row of tubes D¹ with the lower drum B¹. These tubes through which the feed water is introduced open into a box b¹ with which box, as shown, is also connected the uptake tubes C². E indicates a baffle for directing the furnace gases through the steaming section in connection with a rear baffle indicated at E¹, located at the rear of the tube bank C¹. The lower end of this baffle connects as indicated at E² with an upwardly extending baffle E³ lying in front of the tube bank connecting the rear upper and lower drums. The gases are further directed in upflow through this tube bank by baffles indicated at E⁴ and E⁵. F indicates the outlet passage for gases. G indicates steam tubes connecting the steam space of the drum B with the steam space of the drum B², and G¹ the steam tubes connecting the steam space of the drum B³ with the rear drum B². H indicates water tubes connecting the bottom of the drums B² and B³. h indicates a row of water tubes leading from the fourth drum B³ to the lower drum B¹. As shown, these tubes are located behind the baffle E¹ so that only their lower ends lie in the direct path of the gases circulating through the tube system of the boiler. I indicates a pipe connection for drawing off the water from the drum B¹. J a baffle located in the drum B³. K a baffle located at the top of the drum B³ in front of the take-off passage L.

In operation water entering through the header D passes through the tubes D¹ to the box b¹ of the drum B¹, then passes upward from this box through the tube group C² to the upper rear drum B², thence downward through the tube group C³ to the lower drum, thence upward along the tube group C to the upper front drum B, thence downward through tube group C¹ to the lower drum. Steam from the front upper drum of the steaming section enters the drum B³, the steam pipes G¹ connecting the drum B³ and the drum B² maintaining constant pressure in the drums and the steam being preferably drawn off through the drum B³. In case for any reason the water level should fall rapidly in the boiler the reserve of water contained in the drum B³ will flow promptly into the drum B², thus preventing any material or

dangerous change of water level. The drum B³ being entirely disconnected with the circulatory system of the boiler, the water maintained in it will be in a state of quiescence, thus enabling the steam entering this drum to shed its entrained water and also enabling the true approximate water level of the boiler to be ascertained with fair accuracy by a gauge attached to the drum B³.

While I believe the baffle system illustrated and described as peculiarly well adapted for boilers involving my improvement, it will be understood that my improved device can be advantageously employed with boilers having different baffle systems.

Having now described my invention, what I claim as new and desire to secure by Letters Patent, is:

1. A bent tube boiler comprising a steaming section made up of an upper and lower drum connected by two banks of bent tubes and provided with baffles located between the tube banks and in the rear of the rear bank to direct furnace gases upward along the front bank and downward along the rear bank, said boiler having also a water heating section made up of a drum located approximately on the level of the upper drum of the steaming section and tubes connecting said drum to the lower drum of the steaming section said heating section being provided with baffles for directing the gases upward along the tubes, in combination with a fourth drum located approximately on the level of the upper drums aforesaid, said fourth drum being unconnected with the tube banks forming the main circulatory system of the steaming and water heating elements of the boiler but having steam conduits connecting its steam space with the steam spaces of the other two upper drums and water conduits connecting its bottom with the bottom of the rear upper drum acting to maintain an approximately uniform water level in the so connected drums.

2. A boiler having the features of claim 1 having in addition to the short water conduits connecting the fourth and rear upper drums a row of water conduits extending from the bottom of the fourth drum to the lower drum, said row of water conduits lying at the rear of the rear tube bank of the steaming section and separated therefrom by the baffle by which the gases are directed downward along said bank.

WALTER LOCKE.
